DESIGN FOR A CASING FOR HORIZONTAL BROACHING MACHINE

Kenneth C. Monroe, Hudson, Mass., assignor to
The Lapointe Machine Tool Company, Hudson,
Mass., a corporation of Maine

Application May 21, 1940, Serial No. 92,496

Term of patent 14 years

To all whom it may concern:

Be it known that I, Kenneth C. Monroe, a citizen of the United States, residing at Hudson, in the county of Middlesex and State of Massachusetts, have invented a new, original, and ornamental Design for a Casing for Horizontal Broaching Machine, of which the following is a specification, reference being had to the accompanying drawing, forming part thereof.

The figure is a perspective view of a casing for

horizontal broaching machine embodying my new design.

The other side of the article illustrated, not shown, is substantially like the side shown, and the right end, not shown, is substantially plain.

I claim:

The ornamental design for a casing for horizontal broaching machine, as shown and described.

KENNETH C. MONROE.
